UNITED STATES PATENT OFFICE.

HENRY ALEXANDER POLHEMUS, OF BUFFALO, NEW YORK.

PORTABLE ENAMELING-OVEN.

1,109,545.

Specification of Letters Patent. Patented Sept. 1, 1914.

Application filed May 21, 1913. Serial No. 769,101.

To all whom it may concern:

Be it known that I, HENRY A. POLHEMUS, a citizen of the United States, residing at Buffalo, in the county of Erie and State of New York, have invented a new and useful Portable Enameling-Oven, of which the following is a specification.

This invention relates to a portable enameling oven and more particularly to an oven adapted to bake enameling upon passenger and other cars.

An object of the present invention is to provide a baking and enameling oven which is portable and suspended from overhead trolleys whereby the oven may be moved from car to car as desired.

A further object is to provide an enameling oven with air vents in the walls thereof whereby a proper circulation of air may be maintained and to further provide a sliding strip connected to the lower extremities of the side walls which may be raised or lowered as desired. The sliding strip provides for a regulation of heat of the oven and also provides ventilating means therefor.

A further object is to provide an enameling oven which is suspended from an overhead trolley whereby the said oven may be moved out of the way when not in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:

Figure 1 is a side view in elevation of my improved enameling oven as suspended from an overhead trolley. Fig. 2 is a cross sectional view thereof taken on the line A—A of Fig. 1 and with the end door of a somewhat modified form. Fig. 3 illustrates a section taken through one of the side walls and showing the manner in which the strip may be raised and held in such position. Fig. 4 illustrates a modified form of side wall in which the sliding strip is omitted.

Referring to the drawings in which simi-

lar reference numerals designate corresponding parts throughout the several views, the oven comprises the side walls 1 and the top 2 extending thereacross. As illustrated in Fig. 4 of the drawings, the side walls and top may be formed of the two metal plates 3 spaced a suitable distance apart and inserted therebetween is the heat insulating substance 4.

As illustrated in Figs. 1, 2 and 3 of the drawings the side wall 1 is provided with a longitudinal strip 5 slidably secured to the lower edge thereof by the guides 6 whereby the said strip may be raised or lowered, there being suitable latches 7 adapted to engage eyes 8 secured to the side walls 1 and strip 5 respectively, whereby the strip may be maintained in a raised position. Also there are suitable bolts 9 so arranged that the strip 5 may be locked in its lower position. The form of side wall illustrated in Fig. 4 differs from the foregoing in the fact that the side wall 1 is projected downwardly for a slight distance and the strip 5 is dispensed with.

Hingedly secured along the top of the oven and at the ends thereof are the swinging doors 10 which act as a closure for the oven ends and serve to retain the heat therein. The doors 10 are hingedly secured to the top as at 11 and in order to provide means whereby the doors may be held in raised and also in adjusted positions, a rope or flexible connection 12 is rigidly secured to the lower portion of the door as at 13 and extends over a superstructure 14 rigidly secured to the top of the oven and at the side edges thereof. The said flexible connection or rope 12 then extends downwardly and engages a suitable tying post 15 arranged at a convenient point upon the side wall 1.

A somewhat modified form of door is illustrated in Fig. 2 of the drawings in which the door is of the folding or collapsible type and comprises a plurality of vertical sections 16 hingedly secured together and hingedly secured to the side walls 1. The said modified form of door is adapted to fold toward the center and is used when a number of cars are positioned adjacent and little or no room is available therebetween and an upwardly swinging door would be useless.

The side walls of the oven are provided with a number of openings 17 extending therethrough and adjacent which openings

are the flap valves 18 pivotally secured in position and which flaps are adapted to regulate the area of the exposed portion of the openings. These openings 17 are adapted to allow a certain quantity of air to flow therein and to circulate throughout the interior of the oven, and in order to provide a suitable escape for the air after the same has remained within the oven for a considerable time, the outlets 19 are provided at the top of the oven and act in conjunction with the inlet openings 17 to maintain a constant circulation of air throughout the oven.

15 A conventional type of thermometer or other temperature recording device 20 is illustrated upon the side wall of the oven and is adapted to register the temperature maintained therein. The strip 5 may be raised while the oven is moved about and also may be raised for the purpose of ventilating and cooling the oven should the temperature thereof rise to too high a point.

20 In order to mount the oven in a portable manner, the overhead trolley is provided and comprises the horizontal beams 21 supported upon suitable posts 22 and upon which beams are mounted the wheels 23. A suitable suspending structure 24 is carried 25 by the wheels 23 and rigidly secured to the top of the oven. The posts 22 which support the overhead trolleys are positioned at the sides of the track rails 25 beneath which rails are disposed the heating coils 26, the latter supplying the heat for the baking of the enamel.

25 With the above construction as I have described the same, the overhead track and hangers allow the oven to be moved about and brought over a passenger car which is positioned upon the rails 25 above the coils 26 and the end doors 10 or 16 are then closed and the ventilators 17 and 19 adjusted so that the temperature registered by the thermometer 20 reaches the desired

point. The side strips 5 having been previously lowered are adapted to contact with the floor so that the regulation of air may be completely controlled by the ventilators. The oven will be maintained over the passenger car until the paint or enamel upon the interior and exterior thereof is sufficiently and completely baked. The oven being portable may be moved from car to car and when not in use may be moved out of the way, the overhead track extending to a place where the oven will take up little or no shop room.

Having thus fully described the invention what I claim to be new and original with me is:—

1. An enameling oven comprising a top and side walls, longitudinally extending strips movably secured to the lower extremities of said side walls, means for locking said strips in a raised position, means for locking said strips in a lowered position, the side walls provided with valve controlled openings extending therethrough, said top provided with ventilating openings extending therethrough, and swinging doors positioned at the ends of the said oven.

2. An enameling oven comprising an open-ended chamber, hingedly mounted end doors secured thereto, means for holding the same in an open position, longitudinal strips secured to the lower extremities of the side walls of the chamber, means for locking said strips in a raised and lowered position, said chamber provided with openings extending through the top and side walls thereof, and valves controlling the said openings.

In testimony that I claim the foregoing as my own, I have hereto affixed my signature in the presence of two witnesses.

HENRY ALEXANDER POLHEMUS.
